[57] CLAIM

The ornamental design for a handle body for a fishing
rod, substantially as shown and described.

DESCRIPTION

FIG. 1 is a side elevation view of a handle body for a
fishing rod showing my new design.

FIG. 2 is a top plan view.

FIG. 3 is a vertical sectional view taken along line 3—3
of FIG. 1.

FIG. 4 is a bottom plan view.

FIG. 5 is a vertical sectional view taken along line 5—5
of FIG. 1.

FIG. 6 is a vertical sectional view taken along line 6—6
of FIG. 1.

The broken line showing the grip, rod and foregrip is
for environmental purposes only and forms no part of
the claimed design.

FIG. 2

FIG. 1

FIG. 3

FIG. 4

FIG. 6

FIG. 5
